 Telephone Laboratories, Incorporated, New
 York, N. Y., a corporation of New York

Application December 29, 1944, Serial No. 570,440

9 Claims. (Cl. 315—21)

1

This invention relates to arrangements used for the automatic counting of electrical impulses and the like which heretofore has been accomplished by what are known as vacuum or gas-discharge tube counting rings, heretofore described in numerous patents and in technical literature, as, for example, the book "Electrical Counting," by W. P. Lewis, published by Cambridge University Press (1942).

More particularly the invention relates to the use of cathode-ray tubes having a plurality of discrete target anodes, arranged in one or more substantially straight rows, as a substitute for tube ring circuits of the prior art, whereby a considerable economy can be effected due to the reduction in apparatus and complexity of arrangements.

An object of the invention is to cause the electron beam of a cathode-ray tube, of the character described, to advance step-by-step at the frequency of an applied wave over all the target rows and to cyclically repeat this operation during the application of said wave.

A feature of the invention whereby the foregoing object is attained resides in means, including a predetermined one of the targets of each row, responsive to said beam impinging thereon to return said beam to the first target of the row and repeat the cycle in the case of single row tubes or to return the beam to the first target of the next row and so on in the case of tubes having a plurality of rows.

In the case where a plurality of tubes are required, a further feature resides in means responsive to the beam of the first tube impinging on a predetermined target thereof to extinguish that beam and initiate a beam in the next tube, which beam will then be deflected in a similar manner as before across its corresponding targets.

A further feature of the invention resides in employing a cathode-ray tube having a plurality of parallel rows of targets and means for deflecting the beam so that it will be successively stepped across each row in turn.

The invention will be understood from the following description when read in connection with the accompanying drawings:

Fig. 1 of which shows a cathode-ray tube having a single row of target anodes;

Fig. 2 shows a pair of cathode ray tubes each having a single row of target anodes together with means for disabling each tube as soon as its beam reaches the last target, for conditioning the other tube for a subsequent operation, and repeating the cycle;

Fig. 3 shows a tube having a plurality of parallel rows of target anodes (two in the drawing) together with means for successively deflecting the beam from row to row; and

Fig. 4 shows a so-called "staircase" sweep circuit for controlling the step-by-step beam deflection of the cathode ray tubes shown in any of the first three figures.

The operation of the arrangement of Figs. 1 and 4 will first be described:

Referring to Fig. 1 of the drawing, a cathode-ray tube CR1 has been shown which is provided with the usual filament connected to a suitable source of current for the production of an electron beam through the tube, which beam is employed to control a plurality of work circuits connected to target anodes indicated collectively by the reference character 1 located in the end of the tube which will be referred to hereinafter. A control anode 2 is also provided to control and concentrate the electron beam in a well-known manner for the purpose of controlling the deflection of the beam so that it will impinge on the target anode in a desired manner. A pair of deflecting plates 3 are provided and so positioned within the tube as to cause the desired beam deflection when a predetermined potential exists between them. For the purpose of applying potential to the deflecting plates 3 to cause the beam to be deflected so that it will successively impinge on the individual target anodes 1, for example from top to bottom a so-called "staircase" sweep circuit, shown in Fig. 4, is provided which comprises a double circuit rectifier tube 4 having two anodes and two cathodes contained in a single envelope, although two single tubes could obviously be employed, and also four thermionic vacuum tubes 5, 6, 7 and 8, the circuits of which are so arranged that when a predetermined source of potential is applied thereto, a predetermined maximum potential is applied over a deflection conductor 9 to the deflection plates 3 of the cathode-ray tube of Fig. 1 and, when successive negative control impulses are applied to the sweep circuit over the input conductor 10, the potential on the deflecting plate of the cathode-ray tube is progressively reduced in substantially equal steps to cause the cathode beam to move downward from target to target until the last or control target is reached whereupon the sweep circuit recycles thereby raising the potential of the deflecting plates 3 to the original maximum value to sweep the beam back to its top or starting target 55 from which point the beam continues to again

move across the targets under control of the incoming pulses.

When the system is energized by connecting battery thereto, thermionic vacuum tubes 5, 6, 7 and 8, immediately start to conduct plate current and a potential is built up across the cathode resistance 11, of tube 5 which is applied across the deflecting plates 3 of cathode-ray tube CR1 sufficient to deflect the cathode beam to the extreme top of the row of target anodes. Tube 6 also conducts at this time and charges the large capacity condenser 12 connected to its cathode. Further tubes 7 and 8 which constitute a well-known arrangement having certain of the characteristics of a "flip-flop" circuit and other characteristics of a "multivibrator" circuit, each start to conduct but due to the constants of the circuit connections and the negative bias on the grid of 7, the plate current in 8 builds up faster than that of 7 and consequently the drop across the anode resistance of 8 applies an added negative bias to the grid of 7, thereby decreasing the current therein until a point is reached when 7 is blocked and 8 is passing maximum current. At this point the drop across the anode resistance of 8 applies a sufficient negative potential to the grid of 6, to block this tube which however, has been conducting for a sufficient interval to charge condenser 12. Tubes 5 and 8 are now conducting, condenser 12 is fully charged and the potential drop across resistance 11 in the cathode circuit of 5 is applied across deflecting plate 3 of the cathode-ray tube CR1 which holds the beam to the upper target of the row. If now a succession of alternate negative and positive impulses are transmitted over the control conductor 10, the first negative impulse causes the transfer of a small increment of charge on condenser 12 to the small capacity condenser 13 in the control lead thereby decreasing the positive bias on the grid of tube 5 by that amount and decreasing its plate current accordingly which in turn decreases the potential across the cathode resistance 11 to lower the potential applied across deflecting plates 3 of the cathode-ray tube thereby causing the beam to be deflected downward through a small angle to impinge on the second anode of the row.

When the succeeding positive impulse is transmitted over the control conductor 10, the condenser 13 is discharged through resistance 14, the left-hand discharge gap of rectifier tube 4 and resistance 11 to ground, thereby establishing a condition whereby the next negative pulse will extract another small increment of potential from condenser 12 and transfer it to discharge condenser 13 as before. Succeeding pulses of alternate negative and positive potential cause the beam of tube CR1 to be deflected step-by-step across the row of target anodes until it impinges on the last or bottom target of the row, whereupon a negative impulse is transmitted over the recycling conductor 15 to the grid of tube 8 thereby momentarily blocking its plate circuit and raising the potential on the grids of tubes 6 and 7 and permitting them to conduct, whereupon condenser 12 receives a renewal charge due to the plate current flowing in tube 6 and the potential on the grid of tube 5 is raised to increase the current flowing in its cathode resistance 11, whereupon the potential on the deflecting plates of the cathode-ray tube is restored to the original high value and the beam is immediately deflected back to impinge on the first or upper target of the row. As soon as the beam leaves the bottom

or recycling target the potential on the grid of tube 8 begins to increase thereby decreasing the potential on the grid of tube 7 and in a very short interval of time, determined by condenser 5 27 and resistances 28 and 29, tube 7 has ceased conducting and tube 8 is again passing its original normal plate current which reduces the potential on the tube 6 and blocks its plate circuit.

The system is now recycled and the beam continues to step across the row of targets and snap back to the starting position in response to the incoming pulses.

The target anodes of tube CR1 can be connected to control any desired work devices, as for example, electronic tubes indicated by the reference character 16, Fig. 1.

Referring to Fig. 2, in conjunction with Fig. 4, it may be desired to employ two or more single row cathode-ray tubes of the type shown in Fig. 1 for the purpose of controlling a larger number of work devices than can be accumulated by a single tube. In such a case an arrangement as shown in Fig. 2 can be used which shows a pair of single row tubes CR2 and CR2' together with thermionic tube means for alternately enabling one or the other of the cathode-ray tubes for beam deflection, and for disabling the other in response to the beam of an enabled tube impinging on the last target of the row. In this case, as in Fig. 1, the beam of an enabled tube is deflected under control of the sweep circuit shown in Fig. 4.

When potential is applied to a system in accordance with Figs. 2 and 4, vacuum tube 17 quickly reaches its conductive condition thereby blocking tube 18 by placing a negative potential on its grid due to the drop across the plate circuit resistance of tube 17. Due to the high positive potential on the plate of blocked tube 18, which potential is applied over conductor 19 to the control anode 20 of cathode-ray tube CR2, this tube is enabled, and due to the low potential on the plate of conducting tube 17, which is applied over conductor 21 to the control anode 22, of tube CR2', this tube is disabled. Also when potential is applied tubes 5 and 8 of Fig. 4, as previously described, assume a steady conducting condition and tube 6 conducts for an interval sufficient to charge condenser 12. The drop across cathode resistance 11 of tube 5 is applied over conductor 9 to the deflecting plates of both cathode-ray tubes CR2 and CR2', but as the control anode 22 of tube CR2' is negative due to the fact that tube 17 is conducting, the tube CR2' is disabled, i. e., blocked. Due to the positive potential on the control anode 20 of CR2, this tube is enabled and the high potential on its deflecting plate causes its beam to be deflected and impinged on the extreme upper target of the row. As alternate negative and positive pulses are received over conductor 10, the potential across the deflecting plates of CR2 is reduced step-by-step thereby causing the beam of this tube to move downward over the target row until it impinges on its lowermost target whereupon the grid of tube 17 is driven negative by a sufficient amount to stop current flow in its plate circuit thereby raising the potential of its anode which potential is applied over conductor 21 to the control anode 22 of cathode-ray tube CR2' thus enabling it. This increased potential is also applied to the grid of tube 18 which immediately starts to conduct thereby decreasing its plate potential which, applied over conductor 19 to the control anode 20 of tube CR2,

disables this tube. This decrease in potential on the plate of tube 18 also applies a negative potential pulse over conductor 15 to the grid of tube 8 in the sweep circuit of Fig. 4 to cause that circuit to recycle and to again apply a maximum potential to conductor 9 which, as before mentioned is connected to the deflecting plates of both the cathode-ray tubes of Fig. 2. At this time, however, tube CR2 is disabled due to the negative potential on its control anode 20, and tube CR2' is enabled due to the fact that its control anode 22 is positive due to the fact that tube 17 is blocked. In view of this condition the beam of tube CR2' now starts stepping downward over its target row, in the same manner as before described for tube CR2, in response to incoming pulses over conductor 10. As soon as the beam of tube CR2' impinges on its lowermost target, the previously described transfer is repeated but in the reverse order, i. e., the system restores to the original condition with CR2 enabled and CR2' disabled due to the so-called "flip-flop" operation of vacuum tubes 17 and 18, i. e., the reduction of anode current in tube 18 and a corresponding increase in tube 17.

When the "flip-flop" arrangement of tubes 17 and 18 reverses its condition and the anode of one tube is reduced in potential and the other anode increased in potential, the increased potential is prevented from counteracting the negative impulse transmitted over the recycling conductor 15 by introduction of unidirectional devices 30 and 31 in conductors 21 and 19 which are so poled as to permit the passage of negative potential current only, positive potential current being blocked. This same result can be obtained without the use of unidirectional devices by the proper choice of circuit constants to give the negative pulses much steeper wave fronts than the positive pulses have and apply the pulses through differentiating circuits.

Fig. 3 shows a cathode-ray tube CR3 having a plurality of rows of target anodes (2 in the figure) together with thermionic means responsive to the deflection of the electron beam to the last target of a row to cause the beam to successively sweep over the individual rows, one at a time, as long as control impulses are applied to the system over conductor 10 of Fig. 4.

As in the previously described embodiments of Figs. 1 and 2, the sweep of the beam is controlled by the sweep circuit of Fig. 4.

When potential is applied to a system comprising Figs. 3 and 4, it will be assumed that thermionic tube 23 becomes conducting and tube 24 is therefore not conducting. Due to this condition, there will be a negative potential on deflecting plate 25 of cathode-ray tube CR3 whose function is to deflect the beam from row to row as it reaches the bottom or end of its step-by-step sweep, and consequently, deflecting plates 25 will be ineffective at this time and the beam will be directed to and impinge on the first or top target of the first or left-hand row.

The tubes of Fig. 4 function at this time in the manner previously described to first apply a maximum potential over conductor 9 to the deflecting plates 26 and to successively cause the beam to step downward over the target of the left-hand row until the bottom target is reached whereupon a negative potential is applied to the grid of conducting tube 23 thus causing the tubes to reverse their conducting condition, i. e., to cause 24 to conduct and cause tube 23 to stop conducting. When the potential on the plate of

tube 24 is decreased due to the lowered resistance of its anode-cathode circuit, negative potential is applied over the recycling conductor 15 to the grid of tube 8 (Fig. 4) to cause the sweep circuit to recycle, as previously described, and cause a maximum deflecting potential to be again applied over conductor 9 to the deflecting plates 26. At this time due to the increased potential on the anode of tube 23, deflecting plates 25 are increased in potential by an amount sufficient to cause the beam to be deflected at right-angles to its sweep direction to impinge on the next or right-hand row of targets, over which row the movement of the beam will now be deflected downward step-by-step under control of the sweep circuit of Fig. 4.

When the beam impinges on the bottom terminal of the second or right-hand row the grid of tube 24 is driven negative thus stopping its flow of plate current and raising the potential on its anode thereby driving the grid of tube 23 positive and operating that tube to conduct again and decreasing the potential on its anode which in turn decreases the potential in control anode 25 to allow the electron beam to revert back to its original position in line with the first or left-hand row of targets. The reduction of potential on the anode of tube 23 again applies a negative impulse over conductor 15 to again recycle the sweep circuit of Fig. 4 whereupon the electron beam of tube CR2 again starts stepping down over the left-hand row of targets.

Unidirectional devices 32 and 33 are inserted between the anodes of tubes 23 and 24 and the recycling conductor 15 in order to permit a high positive potential on the anode of one tube from counteracting the negative recycling impulse applied to conductor 15 from the anode of the other tube. As previously mentioned in connection with Fig. 2 these unidirectional devices can be eliminated by proper choice of circuit constants.

What is claimed is:

1. In an electronic switching circuit, a source of alternating current, cathode ray means comprising a plurality of discrete target anodes, said means being adapted to direct an electronic beam on each of said anodes in progressive step-by-step succession, means energized and controlled by said alternating current to produce an electrical potential which is reduced in substantially equal steps to control the progressive movement of said beam, and other means responsive to a beam impinging on certain of said anodes to cause said anodes to be cyclically retraversed by a beam during production of said electrical potential.
2. In an electronic switching circuit, a cathode-ray apparatus having a series of discrete target anodes, means under the control of an alternating current applied thereto for producing an electrical potential which is reduced in substantially equal steps for deflecting a cathode-ray beam step-by-step to successively impinge on the individual anodes of said series, and other means responsive to a beam impinging on the last anode of said series to cause said apparatus to continuously recycle during application of said alternating current.
3. In an electronic switching circuit, a cathode-ray device, having means for producing an electrical potential which is reduced in substantially equal steps for moving a cathode-ray beam successively, in a step-by-step manner over a plurality of targets, said targets being arranged in one or more groups and means responsive to the

movement of a cathode-ray beam into cooperative relationship with the last target of a group to start the successive movement of a beam over the targets next in order in the total of said targets.

4. In an electronic counting system, means for translating alternating half waves of an applied alternating current into direct current impulses which comprises cathode-ray apparatus including a plurality of discrete target anodes arranged to cooperate with a cathode beam, means responsive to application thereto of said alternating current for producing an electrical potential which is reduced in substantially equal steps to cause a beam to successively impinge step-by-step on all of said anodes, and other means responsive to a beam impinging on the last one of said anodes to cause said anodes to be successively retraversed during application of said alternating current.

5. In a system for automatically counting electrical impulses, a cathode-ray tube, a plurality of target anodes therein and arranged in a substantially straight row, means for producing an electrical potential which is reduced in substantially equal steps for successively deflecting the cathode beam step-by-step from one target to the next across said row and means responsive to the deflection of said beam to a predetermined target of the row to cause said beam to be returned to the first target to repeat its step-by-step deflection across said row of anodes.

6. An electronic switching circuit, the combination which comprises a cathode-ray tube having a plurality of discrete target anodes arranged in a substantially straight row therein, means for deflecting the electronic beam, a source of alternating current, means for translating said alternating current to a wave having a step-like characteristic to control said deflecting means and cause said beam to impinge on individual ones of said anodes in succession, and other means responsive to said beam impinging on a predetermined one of said anodes for recycling the sweep thereof.

7. In an electronic switching circuit, a pair of cathode-ray devices, each having means for deflecting the electronic beam thereof, and also having a plurality of discrete target anodes therein arranged in a substantially straight row, reversible means for alternately enabling one of said devices and disabling the other, means responsive to application of an alternating current wave thereto for producing an electrical potential which is reduced in substantially equal steps to cause the deflecting means of the enabled device to move the beam thereof to successively impinge on individual ones of the respective anodes.

means responsive to the deflected beam impinging on a certain one of said anodes to actuate said reversible means to disable said enabled device and enable the previously disabled device and means responsive to actuation of said reversible means to cause the beam of the enabled device to successively impinge on its corresponding anodes.

8. In an electronic switching circuit, a cathode-ray device, a plurality of substantially straight rows of discrete target anodes therein and vertical and horizontal beam deflecting elements therefor, alternating current controlled means for producing an electrical potential which is reduced in substantially equal steps for energizing one of said deflecting elements to deflect the electronic beam of said device in a direction to sweep over a predetermined one of said rows of anodes in a step-by-step manner, means responsive to the beam impinging on the last anode of a row to control the second of said deflecting elements to shift said beam to cooperate with a succeeding one of said rows of anodes and other means controlled when said beam is shifted to cause said beam to sweep over said succeeding row in the same manner as before.

9. In an electronic switching circuit, a source of alternating current, cathode-ray means comprising a plurality of discrete target anodes, said means being adjusted to direct an electronic beam on each of said anodes in progressive step-by-step succession, means energized and controlled by complete cycles of said alternating current to produce an electrical potential which is reduced in substantially equal steps to control the progressive movement of said beam, and other means responsive to a beam impinging on certain of said anodes to cause said anodes to be cyclically retraversed by a beam during production of said electrical potential.
